SEWING MACHINE

Charles W. Mueller, St. Louis, Mo., assignor to
 Lewis Invisible Stitch Machine Company, St.
 Louis, Mo., a corporation of Maine

Application October 2, 1934, Serial No. 746,519½

31 Claims. (Cl. 112—176)

This invention relates to new and useful improvements in blind stitch sewing machines generally, although more particularly to a machine for use in the manufacture of coats as described

5 in my prior Patent 1,905,391 issued April 25, 1933.

Among the several objects of my invention are to provide a sewing machine having a post for supporting the work whereby a plurality of parallel lines of stitches may be readily formed in 10 the layers of materials, the lines beginning at the left side of the material and working over to the right side thereof; to provide such a post machine with sufficient clearance under the upper arm of the machine for the work as it is fed rearwardly; 15 to provide a vertically movable post for enabling the operator to insert and remove the work; to provide means for normally locking the post against downward movement; to provide manual means for releasing the locking means and for 20 lowering the post without disconnecting or rendering inoperative any of the operating parts of the machine; to provide means for yieldably supporting the work clamp on the post; and to provide means for adjusting the post and the ridge forming 25 element which is mounted thereon whereby fabrics of different weights may be employed or whereby either "blind" stitches or "through" stitches may be made.

With these and other objects in view which will 30 more fully appear, the nature of the invention will be more clearly understood by following the description, the appended claims, and the several views illustrated in the accompanying drawings.

In the drawings:—

35 Figure 1 is a top plan view of a sewing machine embodying my invention.

Figure 2 is a bottom plan view thereof.

Figure 3 is a front elevation thereof, the post and the mechanisms carried thereon being shown 40 in their normal positions.

Figure 4 is a right hand side elevation of the machine.

Figure 5 is a left hand side elevation of the machine, the cover on the forwardly extending upper arm being removed.

Figure 6 is a rear elevation showing the driving connections between the main shaft, the top feed lever, the needle shaft, and the looper shaft.

Figure 7 is an enlarged plan view partly in section, taken directly above the presser foot.

Figure 8 is an enlarged view taken directly below the foot.

Figure 9 is a detail plan view showing the relation between the work clamp and the spring rollers.

Figure 10 is a vertical section taken in the line of feed and showing the post and the mechanisms carried thereon in their depressed positions.

60 Figure 11 is a horizontal sectional view taken on the line 11—11 of Figure 10.

Figure 12 is a vertical sectional view showing the means for vertically guiding the post and the means for adjustably limiting the upper position of the post.

Figure 13 is a perspective view of the post housing, the post, and the removable cover plate arranged in separated relation.

Like reference numerals designate corresponding parts throughout the several figures of the drawings.

By reference to the accompanying drawings, it will be seen that my invention includes a main frame A which comprises a standard 5 having an arm 6 extending laterally from the upper end thereof and terminating in a forwardly extending upper arm 7, and an arm 8 extending laterally from the base of the standard and terminating in a forwardly extending base arm 9; the upper arms 6, 7 being spaced above and disposed in substantial registration with the base arms 8, 9. 10 15 20

Rigidly fixed to the forward or free end of the upper arm 7, is a presser foot B having a centrally located longitudinal opening or slot 10 formed therein.

Journalized in the upper end of the standard 5 and in the upper arm 6 is a main shaft 11. Journalized in the upper arm 7 and extending longitudinally thereof is an oscillatory needle shaft 12 having a needle arm 13 fixed to its front end. This shaft 12 is located directly above the opening 10 of the presser foot B, and attached to the needle arm 13 is a curved needle 14 which reciprocates across said opening. The needle shaft 12 is oscillated from the main shaft 11 by connections which are indicated as a whole by the reference letter X. A looper or spreader 15 cooperates with the needle 14 in the usual manner for forming single thread chain stitches, although any other type of complementary stitch forming mechanism may be employed if desired. This looper 15 is fixed to a looper rod 16 which is mounted in the usual manner in the arm 7 and is driven from the main shaft 11 by connections which are indicated as a whole by the reference letter Y. 25 30 35 40 45 50 55

Located directly under the presser foot B and vertically movable towards and from said foot, is a work supporting post C. This post is rectangular in horizontal cross section, and is mounted in a 2-part stationary well or housing D, one part 17 thereof being integral with and projecting upwardly from the forward end of the base arm 9 and the other part 18 constituting a removable cover for the post and certain movable parts which are located therein. The upper edge of the well D is located below and in spaced relation to the presser foot B, and the upper portion of the post C projects upwardly above said upper edge. The parts 17, 18 of the well D are conjointly formed with a rectangular opening to 60 65 70 75 80 85 90 95

freely receive the post C. The post is guided vertically by means of front and rear vertically disposed grooves 19, 20 formed in the post, and cooperating front and rear vertical guide bars 21, 22 which are removably attached to the inner side face of the well by screws 23 as shown in Figs. 10 and 11. The cover 18 is removably attached in place by screws 24, 24 as shown in Figs. 3 and 11.

5 10 Carried by the post C and bodily movable up and down therewith are a work clamp E and a ridge-forming element F.

The work clamp E is mounted on the upper end of a vertical post 25 by means of a transverse pivot 26, the post 25 being movable vertically in a bore 27 formed in the post C, and being normally urged upwardly by a coil spring 28 located in the bore between the lower end thereof and the post. The post 25 is provided with a lower reduced extension which extends through the coil spring 28 and through an opening in the housing section 17, and stop nuts 29 are threadably engaged with the lower projecting end thereof for contact with the bottom surface of the post C to thereby limit the upward movement of the work clamp E relative to the post C.

20 25 The ridge forming element F is formed by a disc which is supported for backward and forward oscillations or reciprocations on a transverse axis 30 mounted in ears 31, 31 which project upwardly from the post C, the disc being located between the ears and in front of the post 25 of the work clamp E. The axis 30 of the disc F is located below and in parallelism with the path 30 of movement of the needle 14, or in other words, at right angles to the line of feed. The disc is positioned in a longitudinal opening 32 in the work clamp E and is adapted to intermittently project a node of material upwardly through the opening or slot 18 of the presser foot B into needle penetrating position. The disc is sector-shaped in side elevation and includes a rear radial wall 33 which merges with the concentric periphery 34 of the disc. The disc is preferably formed adjacent the radial wall 33 with a transverse groove 35 forming a resultant feed tooth.

30 35 The disc F is oscillated from the main shaft 11 in the following manner:—Journalized in the base arm 8 of the frame and extending longitudinally thereof, is a rock shaft 36 which projects into the standard 5. An eccentric 37 is fixed to the main shaft 11, a rock arm 38 is fixed to the projecting end of the rock shaft 36, and a strap 39 connects the eccentric and the rock arm. A vertically disposed lever 40 is fulcrumed intermediate its ends as at 41 to a lug 42 integral with the rear face of the post C. A rock arm 43 is fixed to the other end of the rock shaft 36, and a link 44 connects this rock arm with the lower end of the lever 40. A horizontal link 45 is pivotally connected at its rear end to the upper end of the lever 40, and at its front end to the disc F at a point below the axis thereof. It will be noted that when the post C is moved vertically, the driving connections between the main shaft and the disc will not be disconnected or rendered inoperative, and consequently the post may be moved vertically while the main shaft is rotating.

40 45 The post C is capable normally of a small free vertical movement to permit not only a variation in the thicknesses of materials being stitched, but also seams being fed over the ridge forming disc F. To this end, the post C is formed with a centrally disposed bore 46 which extends into the post from the lower end thereof, and mounted

within the bore is a core or support 47. A limiting screw 48 passes downwardly through a non-threaded opening in the upper portion of the post C and has its lower end threadably engaged in the core or support 47, the head of the screw 5 being countersunk in the upper surface of the post and functioning to limit the upward movement of the post relative to the core. A space is normally provided between the inner or upper end of the bore and the upper surface of the core 10 as shown in Figure 10, and the height of this space is limited by the head of the screw 48 engaging the core. The upper portion of the core is reduced to form a resultant peripheral recess for receiving a coil spring 49 which engages the 15 bottom wall of the recess and the upper end wall of the bore 46 and functions to yieldably retain the post C against downward movement relative to the core.

20 25 The support or core 47 is normally locked against vertical movement but is capable of being so moved when the core is moved, and the post C, the work clamp E and the disc F are moved with it. To this end, a toggle is connected to the bottom of the core and to the base arm 8 of the 25 main frame, and in the normal or upper position of the core the toggle is spring held in its locked or aligned position, and a manual means is provided for breaking the toggle and lowering the support against the tension of said spring holding means. The toggle includes a horizontal shaft 50 which extends transversely of the base arm 8 and is mounted therein directly below and in spaced relation to the support or core 47. A rock arm 51 is fixed to the shaft 50, and the upper 30 end thereof is pivotally connected as at 52 to the lower end of a link 53 which is pivotally connected as at 54 to the lower portion of the support or core 47. Thus, when the pivots 50, 52 and 54 are in vertical alignment as shown in Figure 4, the support or core is locked against downward movement. A heavy coil spring 55 extends longitudinally within the base arm 8 and has its rear end anchored to a pin 56 fixed to said arm. The forward end of the spring is connected by a 45 link 57 to the rock arm 51. A stop screw 58 is adjustably mounted in the arm 59 which is integral with and extends rearwardly from the rock arm 51. This stop screw 58 limits the rearward pull on the toggle by the spring 55 by reason of said 50 screw contacting the base arm 8 as shown in Figure 4. A forwardly extending lever arm 60 is integral with the rock arm 51 and forms a resultant bell-crank lever, and connected to the outer end of this lever arm 60 is the upper end 55 of a chain 61 which is connected at its lower end to a treadle 62. Although I have shown a treadle connected to the toggle, it will be understood that a knee-press or any other manual means may be substituted if desired.

60 65 In order to feed the material up to and past the needle 14 and disc F, I have provided an intermittent top feed mechanism of the construction shown in my application Serial No. 707,825, filed Jan. 22, 1934. Briefly stated, the feed mechanism comprises a feed dog 63 which is located in rear of the needle and operates through the slot 18 of the presser foot B against the vertically yieldable work clamp E. The feed dog is fixed to the forward end of a feed lever 64 which 70 extends longitudinally within the upper frame arm 7 and is slidably mounted on a fulcrum 65 which is adjustable longitudinally of the lever. The rear end of the lever 64 is connected to an eccentric 66 on the main shaft 11 which coop- 75

erates with the fulcrum 65 to impart backward and forward, and up and down movements to the dog. The eccentric 66 is adjustable, as disclosed in said application, for the purpose of varying the feed stroke of the dog.

In order to positively adjust the normal vertical position of the post C and thereby set the machine for fabrics of different thicknesses, I have provided a hand adjusting screw 67 which is threadably engaged in a downwardly and rearwardly inclined opening extending into the rigid section 17 of the housing D from the front thereof. The inner end of the screw contacts the upper edge of an upwardly and rearwardly inclined lever 68 fulcrumed at its forward end as at 69 to the section 17. The rear end of the lever 68 engages over a screw or shoulder 70 fixed to the left side of the post C. A head 71 which is fixed to the outer or forward end of the screw 67 is provided on its upper inclined face with a scale 72. The head is notched on its under face as at 73 for cooperation with a spring pin 74 mounted on the section 17 to yieldably retain the screw in an adjusted position. Thus, by turning the screw in a clockwise direction, the lever 68 will be swung downwardly and thus through the medium of the shoulder screw 70, the post C will be lowered against the tension of the coil spring 49. Thus by this means the normal or operating position of the disc F may be readily adjusted to suit fabrics of different weights.

Pivotedly mounted on the under face of the presser foot B by pivot screws 76, 76 are levers 77, 77. These levers are disposed on opposite sides of the work clamp E and extend longitudinally thereof. Journaled on the rear end of each lever 77, 77 on a vertical axis 78 is a roller 79 having an inwardly beveled periphery 80. The bevels 80 register with, that is, parallel, the inclined longitudinal edges 81, 81 of the work clamp E. The inner ends of the levers 77 are formed with upwardly extending ears 82, 82 which extend through slots 83, 83 formed in the toe or front portion of the presser foot B. Between the slots 83, 83 the presser foot is formed with spaced upstanding lugs 84, 84 which extend rearwardly from the front edge of the foot. A transverse horizontal pin 85 is positioned in openings 45 formed in the lugs and the ends of this pin project laterally beyond said lugs toward the slots 83. Coil springs 86, 86 have their inner ends disposed around the projecting ends of the pin 85 and bear against the lugs 84, the outer ends 50 of said springs bearing against the ears 82 of the levers 77. Thus the springs normally hold the ears 82 against the outer walls of the slots 83 and thereby yieldably hold the rollers 79 in close proximity to the inclined edges 81 of the work clamp. Thus when fabrics are fed through the machine they are fed over the work clamp E and downwardly between the clamp and the spring rollers 79. This causes the fabric to be curved in the proper manner when the machine 55 is being used for coat work as explained in my Patent 1,905,391 previously referred to, and it will be noted that when cross seams are being fed through the machine or materials of different weights are being stitched from time to time, the spring rollers 79 will automatically accommodate themselves to the passing of the fabric and seams.

In the operation of my machine the normal position of the post C is first adjusted by means 75 of the hand screw 67 whereby the normal posi-

tion of the ridge forming disc F will be set for either making "blind" stitches or "through" stitches. The operator then depresses the treadle 62 which lowers the post C together with the work clamp E and ridge forming element F 5 to the position shown in Figure 10, and the work is then inserted under the foot B while the post is held in its depressed position. The operator then releases the treadle 62 and the spring 55 returns the post to its normal locked position. 10 The material is then fed through the machine in the usual manner, the work clamp E being moved downwardly during each feeding movement of the feed dog to thereby reduce the drag of the work between the foot and the clamp. The ridge 15 forming disc F will be oscillated in timed relation to the needle, and whenever cross seams are encountered, the disc will yield sufficiently by reason of the coil spring 49 to permit said seam being fed rearwardly. In coat work it is 20 desirous to obtain the proper roll to the lapel when stitching the canvas to the body fabric, and by means of the spring pressed rollers 79 cooperating with the inclined edges 81 of the work clamp E, such roll will be effected. 25

It is of course to be understood that the details of structure and arrangement of parts may be variously changed and modified without departing from the spirit and scope of my invention. 30

I claim:—

1. In a blind stitch sewing machine, the combination with a frame including a standard, a base arm extending horizontally therefrom, and an upper arm extending horizontally from the standard and disposed above and in spaced parallel relation to the base arm; of a presser foot fixed to the free end of said upper arm; a main shaft journaled in the standard; a stitch forming mechanism including a horizontally reciprocating needle mounted on the free end of the upper arm above the presser foot and having driving connections with the main shaft; a post connected to the free end of said base arm directly under the foot; a vertically yieldable work clamp mounted on the post for cooperation with the stationary foot; a movable ridge forming element mounted on the post and projecting upwardly through the work clamp for intermittently projecting a ridge of material upwardly through the foot into needle-penetrating position and having driving connections with the main shaft; and means actuated by the main shaft for intermittently feeding the material past the needle. 35 40 45 50 55

2. In a blind stitch sewing machine, the combination with a frame including a standard, a base arm extending horizontally therefrom, and an upper arm extending horizontally from the standard and disposed above and in spaced parallel relation to the base arm; of a presser foot fixed to the free end of said upper arm; a main shaft journaled in the standard; a stitch forming mechanism including a horizontally reciprocating needle mounted on the free end of the upper arm above the presser foot and having driving connections with the main shaft; a post connected to the free end of said base arm directly under the foot; a vertically yieldable work clamp mounted on the post for cooperation with the stationary foot; an oscillatory ridge forming disc mounted on the post and projecting upwardly through the work clamp for intermittently projecting a ridge of material upwardly through the foot into needle-penetrating position and having 60 65 70 75 75

driving connections with the main shaft; and means actuated by the main shaft for intermittently feeding the material past the needle.

3. In a blind stitch sewing machine, the combination with a frame including a standard, a base arm extending horizontally therefrom, and an upper arm extending horizontally from the standard and disposed above and in spaced parallel relation to the base arm; of a presser foot fixed to the free end of said upper arm; a main shaft journaled in the standard; a stitch forming mechanism including a horizontally reciprocatory needle mounted on the free end of the upper arm above the presser foot and having driving connections with the main shaft; a post connected to the free end of said base arm directly under the foot; a vertically yieldable work clamp mounted on the post for cooperation with the stationary foot; a reciprocatory ridge forming element mounted on the post for intermittently projecting a ridge of material upwardly through the foot into needle-penetrating position; means for reciprocating the element comprising a lever fulcrumed intermediate its ends on the post to swing about a horizontal axis, a link connecting the upper end of the lever and the element, and driving connections between the lower end of the lever and the main shaft; and means actuated by the main shaft for intermittently feeding the material past the needle.

4. In a blind stitch sewing machine, the combination with a frame including a standard, a base arm extending horizontally therefrom, and an upper arm extending horizontally from the standard and disposed above and in spaced parallel relation to the base arm; of a presser foot fixed to the free end of said upper arm; a main shaft journaled in the standard; a stitch forming mechanism including a horizontally reciprocatory needle mounted on the free end of the upper arm above the presser foot and having driving connections with the main shaft; a post mounted on the free end of the base arm for limited vertical movements; a spring for yieldably retaining the post against downward movement; a vertically yieldable work clamp mounted on the post for cooperation with the stationary foot; a movable ridge forming element mounted on the post and projecting upwardly through the work clamp for intermittently projecting a ridge of material upwardly through the foot into needle-penetrating position and having driving connections with the main shaft; and means actuated by the main shaft for intermittently feeding the material past the needle.

5. In a blind stitch sewing machine, the combination with a frame including a standard, a base arm extending horizontally therefrom, and an upper arm extending horizontally from the standard and disposed above and in spaced parallel relation to the base arm; of a presser foot fixed to the free end of said upper arm; a main shaft journaled in the standard; a stitch forming mechanism including a horizontally reciprocatory needle mounted on the free end of the upper arm above the presser foot and having driving connections with the main shaft; a post mounted on the free end of the base arm for limited vertical movements; a spring for yieldably retaining the post against downward movement; manually operable means for adjusting the normal height of the post; a vertically yieldable work clamp mounted on the post for cooperation with the stationary foot; a movable ridge forming element mounted on the post and projecting upwardly

through the work clamp for intermittently projecting a ridge of material upwardly through the foot into needle-penetrating position and having driving connections with the main shaft; and means actuated by the main shaft for intermittently feeding the material past the needle.

6. In a blind stitch sewing machine, the combination with a frame including a standard, a base arm extending horizontally therefrom, and an upper arm extending horizontally from the standard and disposed above and in spaced parallel relation to the base arm; of a presser foot fixed to the free end of said upper arm; a main shaft journaled in the standard; a stitch forming mechanism including a horizontally reciprocatory needle mounted on the free end of the upper arm above the presser foot and having driving connections with the main shaft; a post mounted on the free end of the base arm for limited vertical movements; a spring for yieldably retaining the post against downward movement; manually operable means for adjusting the normal height of the post, said means comprising a shoulder on the post, a lever pivoted on the lower frame arm and overlying the shoulder, and a hand screw mounted on the lower frame arm above the lever and engaging the latter; a vertically yieldable work clamp mounted on the post for cooperation with the stationary foot; a movable ridge forming element mounted on the post and projecting upwardly through the work clamp for intermittently projecting a ridge of material upwardly through the foot into needle-penetrating position and having driving connections with the main shaft; and means actuated by the main shaft for intermittently feeding the material past the needle.

7. In a blind stitch sewing machine, the combination with a frame including a standard; an upper arm extending laterally from the upper end thereof and terminating in a forwardly extending arm, and a lower arm extending laterally from the lower end of the standard and terminating in a forwardly extending arm, said upper and lower arms being disposed one above the other; of a presser foot fixed to the free end of the upper arm; a main shaft journaled in the standard; a stitch forming mechanism including a horizontally reciprocatory needle mounted on the free end of the upper arm above the foot and having driving connections with the main shaft; a post mounted on the free end of the lower arm directly below the foot; a vertically yieldable work clamp mounted on the post for cooperation with the foot; a movable ridge forming element mounted on the post and projecting upwardly through the work clamp for intermittently projecting a ridge of material upwardly through the foot into needle-penetrating position; driving connections between the ridge forming element and the main shaft, said connections extending along the lower arm and into the standard; and means actuated by the main shaft for intermittently feeding the material past the needle.

8. In a blind stitch sewing machine, the combination with a frame including a standard, an upper arm extending laterally from the upper end thereof and terminating in a forwardly extending arm, and a lower arm extending laterally from the lower end of the standard and terminating in a forwardly extending arm, said upper and lower arms being disposed one above the other; of a presser foot fixed to the free end of the upper arm; a main shaft journaled in the standard; a stitch forming mechanism including a horizont-

tally reciprocatory needle mounted on the free end of the upper arm above the foot and having driving connections with the main shaft; a post mounted on the free end of the lower arm directly below the foot; a vertically yieldable work clamp mounted on the post for cooperation with the foot; an oscillatory ridge forming disc mounted on the post and projecting upwardly through the work-clamp for intermittently projecting a ridge of material upwardly through the foot into needle penetrating position; means for oscillating the disc comprising a lever fulcrumed intermediate its ends on the post to swing about a horizontal axis, a link connecting the upper end of the lever and the disc, and driving connections between the lower end of the lever and the main shaft, said connections extending along the lower arm and into the standard; and means actuated by the main shaft for intermittently feeding the material past the needle.

9. In a blind stitch sewing machine, the combination with a frame including a standard, an upper arm extending laterally from the upper end thereof and terminating in a forwardly extending arm, and a lower arm extending laterally from the lower end of the standard and terminating in a forwardly extending arm, said upper and lower arms being disposed one above the other; of a presser foot fixed to the free end of the upper arm; a main shaft journaled in the standard; a stitch forming mechanism including a horizontally reciprocatory needle mounted on the free end of the upper arm above the foot and having driving connections with the main shaft; a post mounted on the free end of the base arm for limited vertical movements; a spring for yieldably retaining the post against downward movement; a vertically yieldable work clamp mounted on the post for cooperation with the foot; a movable ridge forming element mounted on the post and projecting upwardly through the work clamp for intermittently projecting a ridge of material upwardly through the foot into needle penetrating position; driving connections between the ridge forming element and the main shaft, said connections extending along the lower arm and into the standard; and means actuated by the main shaft for intermittently feeding the material past the needle.

10. In a blind stitch sewing machine, the combination with a frame including a standard, an upper arm extending laterally from the upper end thereof and terminating in a forwardly extending arm, and a lower arm extending laterally from the lower end of the standard and terminating in a forwardly extending arm, said upper and lower arms being disposed one above the other; of a presser foot fixed to the free end of the upper arm; a main shaft journaled in the standard; a stitch forming mechanism including a horizontally reciprocatory needle mounted on the free end of the upper arm above the foot and having driving connections with the main shaft; a post mounted on the free end of the base arm for limited vertical movements; a spring for yieldably retaining the post against downward movement; manually operable means for adjusting the normal height of the post; a vertically yieldable work clamp mounted on the post for cooperation with the foot; a movable ridge forming element mounted on the post and projecting upwardly through the work clamp for intermittently projecting a ridge of material upwardly through the foot into needle penetrating position; driving connections between the ridge forming element and the main shaft,

said connections extending along the lower arm and into the standard; and means actuated by the main shaft for intermittently feeding the material past the needle.

11. In a blind stitch sewing machine, the combination with a frame including a standard, an upper arm extending laterally from the upper end thereof and terminating in a forwardly extending arm, and a lower arm extending laterally from the lower end of the standard and terminating in a forwardly extending arm, said upper and lower arms being disposed one above the other; of a presser foot fixed to the free end of the upper arm; a main shaft journaled in the standard; a stitch forming mechanism including a horizontally reciprocatory needle mounted on the free end of the upper arm above the foot and having driving connections with the main shaft; a post mounted on the free end of the base arm for limited vertical movements; a spring for yieldably retaining the post against downward movement; manually operable means for adjusting the normal height of the post; said means comprising a shoulder on the post, a lever pivoted on the lower frame arm and overlying the shoulder, and a hand screw mounted on the lower frame arm above the lever and engaging the latter; a vertically yieldable work clamp mounted on the post for cooperation with the foot; a movable ridge forming element mounted on the post and projecting upwardly through the work clamp for intermittently projecting a ridge of material upwardly through the foot into needle penetrating position; driving connections between the ridge forming element and the main shaft, said connections extending along the lower arm and into the standard; and means actuated by the main shaft for intermittently feeding the material past the needle.

12. In a blind stitch sewing machine, the combination with a frame including a standard, a base arm extending horizontally therefrom, and an upper arm extending horizontally from the standard and disposed above and in spaced parallel relation to the base arm; of a presser foot fixed to the free end of said upper arm; a main shaft journaled in the standard; a stitch forming mechanism including a horizontally reciprocatory needle mounted on the free end of the upper arm above the presser foot and having driving connections with the main shaft; a depressible post mounted on the free end of the lower arm directly under the foot; a vertically yieldable work clamp mounted on the post for cooperation with the stationary foot; a movable ridge forming element mounted on the post and projecting upwardly through the work clamp for intermittently projecting a ridge of material upwardly through the foot into needle-penetrating position and having driving connections with the main shaft; means actuated by the main shaft for intermittently feeding the material past the needle; means including a spring for normally holding said post against depression; and manual means for depressing said post against said spring means.

13. In a blind stitch sewing machine, the combination with a frame including a standard, a base arm extending horizontally therefrom, and an upper arm extending horizontally from the standard and disposed above and in spaced parallel relation to the base arm; of a presser foot fixed to the free end of said upper arm; a main shaft journaled in the standard; a stitch forming mechanism including a horizontally reciprocatory

needle mounted on the free end of the upper arm above the presser foot and having driving connections with the main shaft; a depressible post mounted on the free end of the lower arm directly under the foot; a vertically yieldable work clamp mounted on the post for cooperation with the stationary foot; a movable ridge forming element mounted on the post and projecting upwardly through the work clamp for intermittently projecting a ridge of material upwardly through the foot into needle-penetrating position and having driving connections with the main shaft; means actuated by the main shaft for intermittently feeding the material past the needle; releasable means for locking the post against depression, and manual means for releasing said locking means and for depressing said post.

14. In a blind stitch sewing machine, the combination with a frame including a standard, a base arm extending horizontally therefrom, and an upper arm extending horizontally from the standard and disposed above and in spaced parallel relation to the base arm; of a presser foot fixed to the free end of said upper arm; a main shaft journaled in the standard; a stitch forming mechanism including a horizontally reciprocating needle mounted on the free end of the upper arm above the presser foot and having driving connections with the main shaft; a depressible post mounted on the free end of the lower arm directly under the foot; a vertically yieldable work clamp mounted on the post for cooperation with the stationary foot; a movable ridge forming element mounted on the post and projecting upwardly through the work clamp for intermittently projecting a ridge of material upwardly through the foot into needle-penetrating position and having driving connections with the main shaft; means actuated by the main shaft for intermittently feeding the material past the needle; releasable means for locking the post against depression comprising a toggle connection between the post and the lower arm and a spring connecting the toggle and the lower arm for normally retaining the toggle in locked position, and manual means connected to the toggle for breaking the latter and depressing the post against the tension of the spring.

15. In a blind stitch sewing machine, the combination with a frame including a standard, a base arm extending horizontally therefrom, and an upper arm extending horizontally from the standard and disposed above and in spaced parallel relation to the base arm; of a presser foot fixed to the free end of said upper arm; a main shaft journaled in the standard; a stitch forming mechanism including a horizontally reciprocating needle mounted on the free end of the upper arm above the presser foot and having driving connections with the main shaft; a depressible post mounted on the free end of the lower arm directly under the foot; a vertically yieldable work clamp mounted on the post for cooperation with the stationary foot; a movable ridge forming element mounted on the post and projecting upwardly through the work clamp for intermittently projecting a ridge of material upwardly through the foot into needle-penetrating position and having driving connections with the main shaft; means actuated by the main shaft for intermittently feeding the material past the needle; releasable means for locking the post against depression comprising a toggle connection between the post and the lower arm and a spring connecting the toggle and the lower arm for normally retaining the toggle in locked position, and manual means connected to the toggle for breaking the latter and depressing the post against the tension of the spring.

for normally retaining the toggle in locked position; stop means between the toggle and the lower arm for limiting the locking movement of the toggle under the influence of the spring, and manual means connected to the toggle for breaking the latter and depressing the post against the tension of the spring.

16. In a blind stitch sewing machine, the combination with a frame including a standard, a base arm extending horizontally therefrom, and an upper arm extending horizontally from the standard and disposed above and in spaced parallel relation to the base arm; of a presser foot fixed to the free end of said upper arm; a main shaft journaled in the standard; a stitch forming mechanism including a horizontally reciprocating needle mounted on the free end of the upper arm above the presser foot and having driving connections with the main shaft; a depressible post mounted on the free end of the lower arm directly under the foot; a vertically yieldable work clamp mounted on the post for cooperation with the stationary foot; a movable ridge forming element mounted on the post and projecting upwardly through the work clamp for intermittently projecting a ridge of material upwardly through the foot into needle-penetrating position and having driving connections with the main shaft; means actuated by the main shaft for intermittently feeding the material past the needle; releasable means for locking the post against depression comprising a toggle connection between the post and the lower arm and a spring connecting the toggle and the lower arm for normally retaining the toggle in locked position; an adjustable stop screw carried by the toggle for cooperation with the lower arm for limiting the locking movement of the toggle under the influence of the spring, and manual means connected to the toggle for breaking the latter and depressing the post against the tension of the spring.

17. In a blind stitch sewing machine, the combination with a frame including a standard, a base arm extending horizontally therefrom, and an upper arm extending horizontally from the standard and disposed above and in spaced parallel relation to the base arm; of a presser foot fixed to the free end of said upper arm; a main shaft journaled in the standard; a stitch forming mechanism including a horizontally reciprocating needle mounted on the free end of the upper arm above the presser foot and having driving connections with the main shaft; a depressible post mounted on the free end of the lower arm directly under the foot; a vertically yieldable work clamp mounted on the post for cooperation with the stationary foot; a movable ridge forming element mounted on the post and projecting upwardly through the work clamp for intermittently projecting a ridge of material upwardly through the foot into needle-penetrating position and having driving connections with the main shaft; means actuated by the main shaft for intermittently feeding the material past the needle; releasable means for locking the post against depression comprising a toggle connection between the post and the lower arm and a spring connecting the toggle and the lower arm for normally retaining the toggle in locked position; said toggle including a bell crank lever fulcrumed on the lower arm below the post and a link connecting the vertical arm of the bell crank lever with the post, said spring connecting the toggle and the lower arm, and manual means

connected to the horizontal arm of the bell crank lever for breaking the toggle and depressing the post against the tension of the spring.

18. In a blind stitch sewing machine, the combination with a frame including a standard, a base arm extending horizontally therefrom, and an upper arm extending horizontally from the standard and disposed above and in spaced parallel relation to the base arm; of a presser foot fixed to the free end of said upper arm; a main shaft journaled in the standard; a stitch forming mechanism including a horizontally reciprocatory needle mounted on the free end of the upper arm above the presser foot and having driving connections with the main shaft; a depressible post mounted on the free end of the lower arm directly under the foot; a vertically yieldable work clamp mounted on the post for cooperation with the stationary foot; a movable ridge forming element mounted on the post and projecting upwardly through the work clamp for intermittently projecting a ridge of material upwardly through the foot into needle-penetrating position and having driving connections with the main shaft; means actuated by the main shaft for intermittently feeding the material past the needle; releasable means for locking the post against depression comprising a toggle connection between the post and the lower arm and a spring connecting the toggle and the lower arm for normally retaining the toggle in locked position, stop means between the toggle and the lower arm for limiting the locking movement of the toggle under the influence of the spring, said toggle including a bell crank lever fulcrumed on the lower arm below the post and a link connecting the vertical arm of the bell crank lever with the post, said spring connecting the toggle and the lower arm, and manual means connected to the horizontal arm of the bell crank lever for breaking the toggle and depressing the post against the tension of the spring.

19. In a sewing machine, the combination with a frame including a standard, an upper arm extending laterally from the upper end thereof, and a lower arm extending laterally from the lower end of the standard; of a stitch forming mechanism mounted on the free end of the upper arm, a depressible work-supporting post mounted on the free end of the lower arm directly below said stitch forming mechanism, means including a spring for normally holding said post against depression, and manual means for depressing said post against the tension of said spring means.

20. In a sewing machine, the combination with a frame including a standard, an upper arm extending laterally from the upper end thereof, and a lower arm extending laterally from the lower end of the standard; of a stitch forming mechanism mounted on the free end of the upper arm, a depressible work-supporting post mounted on the free end of the lower arm directly below said stitch forming mechanism, releasable means for locking the post against depression, and manual means for releasing said locking means and for depressing said post.

21. In a sewing machine, the combination with a frame including a standard, an upper arm extending laterally from the upper end thereof, and a lower arm extending laterally from the lower end of the standard; of a stitch forming mechanism mounted on the free end of the upper arm, a depressible work-supporting post mounted on the free end of the lower arm directly below said stitch forming mechanism, releasable means for

locking the post against depression comprising a toggle connection between the post and the lower arm and a spring connecting the toggle and the lower arm for normally retaining the toggle in locked position, and manual means connected to the toggle for breaking the latter and depressing the post against the tension of the spring.

22. In a sewing machine, the combination with a frame including a standard, an upper arm extending laterally from the upper end thereof, and a lower arm extending laterally from the lower end of the standard; of a stitch forming mechanism mounted on the free end of the upper arm, a depressible work-supporting post mounted on the free end of the lower arm directly below said stitch forming mechanism, releasable means for locking the post against depression comprising a toggle connection between the post and the lower arm and a spring connecting the toggle and the lower arm for normally retaining the toggle in locked position, stop means between the toggle and the lower arm for limiting the locking movement of the toggle under the influence of the spring, and manual means connected to the toggle for breaking the latter and depressing the post against the tension of the spring.

23. In a sewing machine, the combination with a frame including a standard, an upper arm extending laterally from the upper end thereof, and a lower arm extending laterally from the lower end of the standard; of a stitch forming mechanism mounted on the free end of the upper arm, a depressible work-supporting post mounted on the free end of the lower arm directly below said stitch forming mechanism, releasable means for locking the post against depression comprising a toggle connection between the post and the lower arm and a spring connecting the toggle and the lower arm for normally retaining the toggle in locked position, an adjustable stop screw carried by the toggle for cooperation with the lower arm for limiting the locking movement of the toggle under the influence of the spring, and manual means connected to the toggle for breaking the latter and depressing the post against the tension of the spring.

24. In a sewing machine, the combination with a frame including a standard, an upper arm extending laterally from the upper end thereof, and a lower arm extending laterally from the lower end of the standard; of a stitch forming mechanism mounted on the free end of the upper arm, a depressible work-supporting post mounted on the free end of the lower arm directly below said stitch forming mechanism, releasable means for locking the post against depression comprising a toggle connection between the post and the lower arm and a spring connecting the toggle and the lower arm for normally retaining the toggle in locked position, said toggle including a bell crank lever fulcrumed on the lower arm below the post and a link connecting the vertical arm of the bell crank lever with the post, said spring connecting the toggle and the lower arm, and manual means connected to the horizontal arm of the bell crank lever for breaking the toggle and depressing the post against the tension of the spring.

25. In a sewing machine, the combination with a frame including a standard, an upper arm extending laterally from the upper end thereof, and a lower arm extending laterally from the lower end of the standard; of a stitch forming mechanism mounted on the free end of the upper

- arm, a depressible work-supporting post mounted on the free end of the lower arm directly below said stitch forming mechanism, releasable means for locking the post against depression comprising a toggle connection between the post and the lower arm and a spring connecting the toggle and the lower arm for normally retaining the toggle in locked position, said toggle including a bell crank lever fulcrumed on the lower arm below the post and a link connecting the vertical arm of the bell crank lever with the post, said spring connecting the toggle and the lower arm, stop means between the toggle and the lower arm for limiting the locking movement of the toggle under the influence of the spring, and manual means connected to the horizontal arm of the bell crank lever for breaking the toggle and depressing the post against the tension of the spring.
26. In a blind stitch sewing machine, the combination with a stationary presser foot having an opening therein, of a stitch forming mechanism located above the foot and including a horizontally reciprocatory needle movable across the presser foot opening, a vertically yieldable work clamp located below and cooperating with the foot, said clamp having downwardly inclined side edges, a ridge forming element for projecting a ridge of material upwardly through the presser foot opening into needle penetrating position, a pair of pressure elements mounted on the foot on opposite sides of the work clamp and having inclined faces for cooperation with the inclined side edges of said clamp, and spring means urging the elements towards the clamp.
27. In a blind stitch sewing machine, the combination with a stationary presser foot having an opening therein, of a stitch forming mechanism located above the foot and including a horizontally reciprocatory needle movable across the presser foot opening, a vertically yieldable work clamp located below and cooperating with the foot, said clamp having downwardly inclined side edges, a ridge forming element for projecting a ridge of material upwardly through the presser foot opening into needle penetrating position, a pair of pressure elements mounted on the foot on opposite sides of the work clamp and having inclined faces for cooperation with the inclined side edges of said clamp, spring means urging the elements towards the clamp, and means for limiting the movements of the elements towards the clamp.
28. In a blind stitch sewing machine, the combination with a stationary presser foot having an opening therein, of a stitch forming mechanism located above the foot and including a horizontally reciprocatory needle movable across the presser foot opening, a vertically yieldable work clamp located below and cooperating with the foot, said clamp having downwardly inclined side edges, a ridge forming element for projecting a ridge of material upwardly through the presser foot opening into needle penetrating position, a pair of pressure rollers located below the foot on opposite sides of the work clamp, said rollers having downwardly and inwardly inclined peripheries for cooperation with the inclined side edges of the clamp, means for supporting the rollers on the foot for movements toward and from the

work clamp, and spring means urging the rollers toward the clamp.

29. In a blind stitch sewing machine, the combination with a stationary presser foot having an opening therein, of a stitch forming mechanism located above the foot and including a horizontally reciprocatory needle movable across the presser foot opening, a vertically yieldable work clamp located below and cooperating with the foot, said clamp having downwardly inclined side edges, a ridge forming element for projecting a ridge of material upwardly through the presser foot opening into needle penetrating position, a pair of pressure rollers located below the foot on opposite sides of the work clamp, said rollers having downwardly and inwardly inclined peripheries for cooperation with the inclined side edges of the clamp, means for supporting the rollers on the foot for movements toward and from the work clamp, spring means urging the rollers toward the clamp, and means for limiting the movements of the rollers toward the clamp.

30. In a blind stitch sewing machine, the combination with a stationary presser foot having an opening therein, of a stitch forming mechanism located above the foot and including a horizontally reciprocatory needle movable across the presser foot opening, a vertically yieldable work clamp located below and cooperating with the foot, said clamp having downwardly inclined side edges, a ridge forming element for projecting a ridge of material upwardly through the presser foot opening into needle penetrating position, a pair of pressure rollers located below the foot on opposite sides of the work clamp, said rollers having downwardly and inwardly inclined peripheries for cooperation with the inclined side edges of the clamp, a pair of levers extending longitudinally of the foot on opposite sides of the work clamp and being fulcrumed intermediate their ends on said foot, said rollers being journaled on the inner ends of said levers, and spring means interposed between the foot and the outer ends of the levers for urging the rollers toward the work clamp.

31. In a blind stitch sewing machine, the combination with a stationary presser foot having an opening therein, of a stitch forming mechanism located above the foot and including a horizontally reciprocatory needle movable across the presser foot opening, a vertically yieldable work clamp located below and cooperating with the foot, said clamp having downwardly inclined side edges, a ridge forming element for projecting a ridge of material upwardly through the presser foot opening into needle penetrating position, a pair of pressure rollers located below the foot on opposite sides of the work clamp, said rollers having downwardly and inwardly inclined peripheries for cooperation with the inclined side edges of the clamp, a pair of levers extending longitudinally of the foot on opposite sides of the work clamp and being fulcrumed intermediate their ends on said foot, said rollers being journaled on the inner ends of said levers, spring means interposed between the foot and the outer ends of the levers for urging the rollers toward the work clamp, and cooperating means between the outer ends of the levers and the foot for limiting the movement of the rollers toward the clamp.

CHARLES W. MUELLER.
